UNITED STATES PATENT OFFICE.

HOWARD H. LANNING, OF TOPEKA, KANSAS, ASSIGNOR OF ONE-HALF TO HENRY W. JACOBS, OF TOPEKA, KANSAS.

SPARK-CONTROLLING DEVICE FOR MAGNETO IGNITION.

1,106,953.

Specification of Letters Patent.

Patented Aug. 11, 1914.

Application filed April 5, 1911. Serial No. 619,094.

To all whom it may concern:

Be it known that I, HOWARD H. LANNING, a citizen of the United States, and resident of Topeka, in the county of Shawnee and State of Kansas, have invented a certain new and useful Improvement in Spark-Controlling Devices for Magneto Ignition, of which the following is a description, reference being had to the accompanying drawings, which form a part of my specification.

My invention relates to a device for advancing or controlling the moment or period of sparking or ignition induced by a magneto in connection with an internal combustion engine; and has for its object the production of simple mechanical means whereby the armature of a magneto may be controlled or shifted relatively to the crank or cam shaft of the engine, so that when the armature is revolved or set in operation, the magnetic lines of force of the field will be cut at the proper time to produce the maximum strength of spark, the invention resulting in a device whereby any desired moment of spark or point of ignition in the compression cycle of an internal combustion engine may be obtained, as will more fully appear from the following detailed description.

In the drawings:—Figure 1 is a top plan view of a well known type or form of magneto with my improved device or driving mechanism attached thereto; the device or driving mechanism being shown in cross section. Fig. 2 is a side elevation of the magneto with my improved driving mechanism or spark controlling device secured thereto; the magneto being shown in partial longitudinal section, while a portion of the casing or housing of the driving mechanism is shown broken away in order to disclose the internal mechanism. Fig. 3 is a top plan view of a well known type of magneto, showing a modified construction in cross section of my invention.

My device may be used in connection with any of the various well known types of magnetos which form no part of my invention, so that a specific description of the magneto itself need therefore not be entered into, except to state, that the point in the armature

revolution, at which the interruption of the primary circuit occurs, must be fixed at such a relation to the magnetic fields that all of the wires of the armature will be cutting magnetic lines of force.

For the purpose of illustration, I have shown the magneto 1, preferably secured on a bracket 1^a, which may be cast integral with the engine crank case as shown in Fig. 2; the magneto however may be attached in any suitable manner to the engine. Describing the construction shown in Figs. 1 and 2, it will be seen that the magneto armature spindle 2 is provided with a pinion sleeve 3, which may be securely fastened to the spindle 2 in any suitable manner; for example, the spindle 2 may be tapered as shown, with the pinion sleeve 3 made to conform therewith and securely held in place by the nut 4. If desired, the sleeve 3 may also be held against rotation about the spindle 2 by a key in the well known manner employed for such purposes.

The end of the spindle together with the sleeve secured thereon, as well as the mechanism to be hereinafter described, is inclosed by a suitable casing or housing 6, which is preferably cast integral with the engine crank case or included in the casing of the magneto. As the sleeve 3 is intended to revolve with the spindle 2, suitable bushing 5 is provided about the sleeve 3 and in the opening in the housing 6 as clearly shown in Fig. 1. Secured to the pinion sleeve 3 are the pinions 7, 7. These pinions 7, 7, may be secured to the sleeve 3 in any suitable manner, as for example sleeve 3 may, if desired, be provided with radially extending portions or studs into which the bolts 7^a, 7^a, may be screwed and securely fastened in place. With such a construction, suitable bushing of course is employed as shown at 16 and 17, to permit of the proper rotation of the pinions 7, 7, about their respective axes or bolts. Loosely mounted within the casing or housing 6, and adapted to mesh with pinions 7, 7, is a driven gear or idler 8, which is also provided with teeth on its periphery to adapt it to mesh with the driving gear 9, of which only a portion is shown in the figures. When the magneto armature is to be driven

at cam shaft speed, the driving gear 9 may be the cam shaft gear as shown, or it may be the crank shaft gear if more convenient. If it is desired, however, to drive the armature at cam shaft speed or faster, as would be required for engines of four or more cylinders, on the four-cycle principle, or for engines of two or more cylinders, on the two-cycle principle, then the member or sleeve 3 which carries the pinions 7, 7, should be the stationary member, and be connected to the member or lever 12, and the member or gear 11 be secured to the spindle of the armature and become the armature driving member.

15 The member or gear 8 is adapted to rotate independently of sleeve 3, and I therefore provide bushing 10 of suitable material. A member or gear 11 is provided to the opposite side of the pinions 7, 7, and is loosely mounted within the housing or casing 6, as clearly shown in Fig. 1. This gear is shown provided with a spindle 11^a, which takes through and has suitable bearing in the side of the casing 6, as clearly shown; the outer 20 end of the spindle 11^a, being provided with a lever 12, which is securely clamped or held thereon so that movement of gear 11, may be controlled and depend upon movement of lever 12.

30 In order to prevent unnecessary wear and at the same time maintain the respective parts of the device in their relative positions, collars 13, 14, and 15, and bushing 18, of any suitable anti-friction material are provided, 35 as shown in Fig. 1.

It is apparent from the construction shown in Figs. 1 and 2 that driving gear 9 will rotate the idler or driven gear 8 which in turn will rotate pinions 7, 7, about their axes.

40 As these pinions 7, 7, mesh with the gear 11, which is normally stationary, it is evident that pinions 7, 7, will also be compelled to move through a circle or orbit and thus rotate armature 2 through the medium of pinion sleeve 3.

When the control member or lever 12 is held stationary, and the pinions 7, 7, are driven by the gear 8, the armature will initially remain in the same relative position with respect to its magnetic field. By shifting the lever 12, the gear 11 will be moved, thereby imparting movement to the pinions 7, 7, relative to the orbit or circle described, either advancing or retarding their progress 55 along the orbit.

With gear 11 stationary, which is its normal condition until it is desired to shift the armature of the magneto with relation to the field, gear 8 will travel at just twice the speed that the pinions 7, 7, will drive pinion sleeve 3, together with the armature of the magneto; the arrangement of the gear being such that the idler or driven gear 8 will rotate two revolutions to one revolution of the magneto armature.

In the modifications shown in Fig. 3, it will be seen that driving gear 9 meshes with, and rotates, gear 8, as previously described, and gear 8 meshes with pinions 7, 7, secured to the member or spider 3^a. The member or spider 3^a is normally stationary and is provided with the spindle 3^b to which lever 12 is secured. It is of course understood that the pinions 7, 7, rotate upon their respective axes. Pinions 7, 7, in turn mesh with the gear 11^b, which in this construction is secured to the spindle of the armature. When this construction is employed, in order to advance or retard the moment of sparking, lever 12 must be moved in the proper direction which will compel member 3^a with the pinions 7, 7, to rotate, and by reason of the fact that gear 8 is held stationary by driving gear 9, gear 11^b will be compelled to move in the same direction with member or spider 3^a and thereby rotate the armature accordingly.

It is evident from the construction shown and described that the differential motion, which may be obtained by the arrangement of the driving mechanism of the magneto, is such that the control lever 12 should be moved twice the distance of the desired movement or rotation of the armature, in the construction shown in Figs. 1 and 2; or, when the construction shown in Fig. 3 is employed, lever 12 should be moved just half the distance of the desired movement or rotation of the armature. For example, should it be desired to advance the spark or ignition point, that is, to hasten the moment of cutting the lines of force of the field by the armature, referring now to the construction shown in Figs. 1 and 2, lever 12 must be moved in a direction that will rotate gear 11 in the same direction as that of idler or driven gear 8; this will increase the speed of member 3 and necessarily increase the speed of pinions 7, 7, in their movement through the circle or orbit; but when the construction shown in Fig. 3 is employed, lever 12 must be moved 100 in a direction that will rotate member 3^a together with pinions 7, 7, in the same direction that it is intended to move gear 11^b and the armature. If it is desired to retard the spark or ignition point, namely delay 110 the moment of cutting the magnetic lines by the armature, referring again to Figs. 1 and 2, lever 12 must be moved in the opposite direction, thereby necessarily rotating gear 11 in the direction opposite to the movement of gear 8; the differential movement resulting in a greater length of time being consumed by pinions 7, 7, in describing their circle or orbit. As in the case of advancing the spark, lever 12 should be moved 120 twice the distance necessary to move or shift the armature to retard the spark or ignition point the desired degree.

When it is desired to retard the spark, namely delay the moment of cutting the 125

magnetic lines of force by the armature, in the construction shown in Fig. 3, lever 12, as in the case of the constructions shown in Figs. 1 and 2, must be moved in the opposite direction, which will rotate spider or member 3^a together with pinions 7, 7, in a direction opposite to the movement of gear 8. As gear 8 of course cannot be moved against the action of gear 9, it is evident that such rotation of the member or spider 3^a and its pinions 7, 7, will compel gear 11^b, together with the armature, to rotate in the same direction, thereby causing the armature to be moved backward a certain distance and delay the moment of cutting the magnetic lines of force by the armature. When using the construction shown in Fig. 3, lever 12 should be moved just half the distance it is desired to rotate the armature, as previously stated in connection with the description of the device when it is intended to advance the moment of sparking.

It is evident from the constructions that any desired advancement or retardation of the spark or ignition point may be effected without interfering with the speed of the driving and driven members or gears, by the rotation of the gear or member 11, with the construction shown in Figs. 1 and 2, or rotation of member 3^a in the construction shown in Fig. 3, through the manipulation of lever 12; so that, in order to obtain complete combustion and a resultant maximum pressure at the beginning of the power stroke of the piston, where the engine is operating at a slow speed, the moment of ignition is retarded by what may be termed a reverse movement of lever 12, causing a greater period of time to be consumed by the pinions 7, 7, in describing the circle or orbit in Figs. 1 and 2; or causing more time to be consumed by gear 11^b, in Fig. 3, in completing its revolution; while on the other hand, where the speed of the engine increases, the moment of ignition must be advanced or made earlier, which is induced by the forward movement of lever 12, thereby causing a lesser period of time to be consumed by pinions 7, 7, in describing the circle or orbit with the construction shown in Figs. 1 and 2; or causing the gear 11^b to be advanced in its revolution when employing the construction shown in Fig. 3. With my invention however, the revolving armature will at all times cut all the lines of force of the field and thus produce a spark of maximum strength. With the arrangement of gearing as shown in Figs. 1 and 2, where the driven gear or idler 8 rotates two revolutions to the armature's one, a driven gear or idler of smaller diameter may be employed, thus permitting of a more compact and desirable construction.

I have shown and described what I believe to be the simplest and best forms of

my invention for producing the results thereby obtained; as the constructions however may be varied in certain minor details without departing from the spirit of my invention, I do not wish to be understood as limiting myself to the exact constructions shown and described, but

What I claim and wish to secure by Letters Patent is:—

1. A spark controlling device for magneto ignition, comprising, in combination with a driving gear, a train of gears, a portion of said gears being connected with the armature and arranged to rotate about axes extending at right angles to the armature and also to move through a circle or orbit, a normally stationary gear meshing with the gears connected with the armature, and means for operating said normally stationary gear whereby movement is imparted to the portion of gears connected with the armature independent of that imparted thereto by the remaining portion of said train of gears.

2. A spark controlling device for magneto ignition, comprising a set of independently movable gears, means connected with the armature and adapted to be controlled by said gears, one of said gears acting as the power imparting gear, while the other gear is normally stationary and adapted to impart independent movement to said means and control the relation of the armature to the crank-shaft of the engine without affecting the number of lines of force of the magnetic field cut by the armature and means for operating said normally stationary gear.

3. A spark controlling device for magnetic ignition, comprising, in combination with the armature of a magneto having a stationary field, a pair of independent, oppositely disposed gears, means operatively connected with the armature and arranged between the pair of gears, and means connected with one of said gears, which gear is normally stationary, whereby the latter may be moved in either direction independently of the movement of the opposite gear and thereby impart movement to the means independent of the movement given thereto by the oppositely disposed gear and thereby control the movement of cutting the magnetic lines of force by the armature.

4. In combination with the armature of a magneto having a stationary field, a spark controlling device comprising means extending at right angles to the armature and operatively connected therewith, said means being adapted to rotate about an axis and also to describe a circle whose center is coincident with the axis of the armature, mechanism arranged in operative relation with said means whereby the latter is rotated and moved about the circle, and normally stationary means engaging with said first mentioned means whereby the latter may be controlled

in the movement through the circle and thereby control the moment of cutting the magnetic lines of force by the armature.

5. In combination with the armature of a magneto, a spark controlling device comprising a series of members whereby the armature is rotated, the intermediate portion of said series of members being arranged to rotate on independent axes and to 10 describe an orbit, while another portion of said series is normally stationary and so related to the other portion of said series of members that it will cause a relative reduction in speed between the driving member of 15 the series of members and the armature, while movement of said stationary portion of series of members will induce differential motion and cause the moment of sparking to be either advanced or retarded, and means 20 for controlling the normally stationary portion of said series of members.
6. In combination with a magneto having a stationary field and the armature, a spark controlling device comprising a series of rotating, meshing members intermediate of a member driven by the engine and the armature, one of said members being normally held against rotation and causing a relative reduction in speed between the member 25 driven by the engine and the armature, and means whereby said member may be moved 30

in either a forward or backward direction and similar movement given to the member connected with the armature.

7. A spark controlling device for magneto ignition, comprising a casing, a series of meshing members arranged within said casing, one portion of the series being normally stationary but with all of the members adapted to move about a common axis, while 40 a portion of the series of members has additional movement about an axis extending perpendicular to the first mentioned axis, the portion of the series which is normally stationary being provided with a spindle extending through the side wall of the casing, means whereby a bearing for said spindle is provided and lateral movement thereof prevented, and means secured to said spindle whereby the latter together with said portion of series of members attached thereto may be given an independent movement either forward or backward and thereby 45 control the relation of the armature to the crank-shaft of the engine without affecting 50 the number of lines of force of the magnetic field cut by the armature.
